(57) **CLAIM**

The ornamental design for a hospital gown, as shown and described.

DESCRIPTION

FIG. 1 is a perspective view of a hospital gown showing my new design;

FIG. 2 is a front elevational view thereof;

FIG. 3 is a rear elevational view thereof, particularly showing the hospital gown partially opened showing the interior;

FIG. 4 is a left-side elevational view thereof;

FIG. 5 is a right-side elevational view thereof;

FIG. 6 is a top plan view thereof; and,

FIG. 7 is a bottom plan view thereof.

The broken lines of the medical devices and elements of the hospital gown depict features that form no part of the claimed design. The broken lines that depict the partial human figure depict how the hospital gown may appear in a position of use and forms no part of the claimed design.
